United States Patent Office.

ROBERT H. BIRT, OF KOKOMO, INDIANA.

Letters Patent No. 67,097, dated July 23, 1867.

IMPROVEMENT IN TINNERS' FOLDING MACHINE.

The Schedule referred to in these Letters Patent and making part of the same.

TO ALL WHOM IT MAY CONCERN:

Be it known that I, ROBERT H. BIRT, of Kokomo, in the county of Howard, and State of Indiana, have invented a new and useful Improvement in Pan-Folding Machines for Tinners' Use in the manufacture of pans from sheet metal, consisting in novel combinations and arrangements of mechanical devices; and I do hereby declare that the following is a full, clear, and exact description of said improved machine, reference being had to the annexed drawings, making part of this specification, in which—

Figure 1 is a perspective view.

Figure 2 is a transverse vertical section; and

Figure 3 is an end view.

The same letters are employed in all the figures in the indication of identical parts.

A is the bed-piece supporting the other parts of the mechanism. To one end of the bed-piece is attached the standard B, having on its inner face the inclination intended to be given to the sides of the pan. C is a standard of similar form, but movable, being attached to the bed-piece by a set-screw passing through a longitudinal slot through the bed-piece. D is a lever hinged to the stationary standard B, and having a longitudinal slot in the middle, and another one in the end. E is a stationary former attached to the lever, and having one face inclined at an angle corresponding to that of the stationary standard B. E² is a similar former, the face of which corresponds to the angle of the movable standard C. This piece is attached to the lever D by a set-screw passing through the longitudinal slot in the middle of the lever D. E¹ is a movable piece, filling the space between the pieces E and E², and also attached to the lever in the same manner as the latter. F is a lever, attached to the bed-piece A by a rod passing through lugs projecting from the latter. This lever has shoulders which compress and retain in position the lever D when pressed down, the lever entering the slot in the end of the lever D. G is a folding door serving as a lever, hinged to lugs on the side of the bed-piece, operated by the handle K. H are spring-gauges, formed as shown in fig. 2, the curved part passing under the folding lever G, through transverse slots in the latter. These springs are adjustably attached by set-screws passing through slots in the projection I. The object of these springs is to gauge the depth of the pan. To make either a deep or low pan by setting the gauges.

This pan-folder is operated as follows: The piece to form the (entire) pan being cut to the proper size, the adjustable stand C is set so as to allow the sheet or plate to lie flat upon the bed-piece; the plate or sheet is extended through on to the bed-piece, and under the lever D, until the end of the plate or sheet touches the gauges H in the projection I. The plate is then held permanently by means of the lever D, which is held by the lever F. The folder G, lying down on a level with the bed-piece, is then raised to the position in the drawing by means of the handle K, enclosing one end of the plate between the lever D and the folder G, which forms the flange to one end. The other end is done the same way. The sheet, with two ends or flanges, is put upon the bed-piece, with one side extending to the gauges H, and held there by the lever D, (as when the end was folded,) and the standard C and former E² so adjusted that the fold on one end of the plate will stand between the standard B and the former E, and the other fold will stand between the standard C and former E², when the folder G is again raised by the handle K to an upright position, as in the drawing, which completes the ends and one side. The other side is done the same way, which completes the pan, except the wire and turning of corners. The lever D may be used by a spring at each end, which will throw it up at each end, and may be worked by the hand or foot to an advantage.

What I claim as my invention, and desire to secure by Letters Patent, is—

1. The combination of the bed-plate and stationary standard B with the adjustable standard C and lever D, and former E and adjustable former E², substantially as and for the purpose set forth.
2. The combination of the parts A, B, C, D, E, and E², constructed and arranged substantially as described, with the folding door or lever G, substantially as and for the purpose set forth.
3. The door or lever G in combination with the adjustable springs H, constructed and arranged substantially as and for the purpose set forth.

In testimony whereof I have signed my name to this specification in the presence of two subscribing witnesses.
